Primary Examiner—Martie K. Holtje[57] **CLAIM**

The ornamental design for a bingo dabber, as shown and described.

DESCRIPTION

FIG. 1 is a front elevational view of the bingo dabber showing my new design;

FIG. 2 is a rear elevational view thereof;

FIG. 3 is a right side view thereof;

FIG. 4 is a left side view thereof;

FIG. 5 is a top plan view thereof, the dotted line showing of the reverse letters WIN being for illustrative purposes only and forming no part of the claimed design; and,

FIG. 6 is a bottom plan view thereof.
